(57) **CLAIM**

The ornamental design for a cradle for electronic device, as shown and described.

DESCRIPTION

FIG. 1 is a front perspective view of a cradle for electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a left side cross-sectional view taken along the line 8-8 of FIG. 6.

The numbers, arrows, and associated broken lines in FIG. 6 represent a plane along which a cross-sectional view is taken and form no part of the claimed design.
